UNITED STATES PATENT OFFICE.

LEROY E. SPENCE AND JOSEPH R. HOGATE, OF BLADEN, NEBRASKA.

REENFORCED GLASS SUBSTITUTE.

Application filed October 4, 1928. Serial No. 139,524.

The invention relates to glass substitutes and has for its object the fabric base with transverse and longitudinally disposed strands of heavier thread or of wire, which will thoroughly brace the fabric, hold the same together after deterioration has set in incident to the deterioration of the threads of the fabric, and at the same time bulging of a sheet of material when in position will be prevented.

A further object is to provide a glass substitute having a fabric base and longitudinally and transversely disposed strands of heavier material thereby forming recesses in which the paraffin or other material used will be relatively heavy, thereby additionally bracing the fabric, and in combination with the large reenforcing strands providing a glass substitute which will stand up under all conditions of weather, and one which will transmit the maximum quantity of ultra-violet rays, which is conducive to the health of human beings as well as poultry and plant life. The squares formed by the reenforced strands absorb more of the processing mixture, and in the cooling process tends to give a more evenly finished product and insures longer and more satisfactory wearing qualities and at the same time the advantages of a heavier material are obtained without loss of its translucent qualities which would be the case with a heavy fabric, and at the same time the lighter fabric reenforced can be easily handled which is not the case with lighter fabric.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:

Figure 1 is a plan view of a sheet of material showing the reenforcing strands therein.

Figure 2 is a plan view of a portion of the fabric showing the reenforcing strands therein.

Figure 3 is a perspective detail sectional view through a portion of the sheet of material.

Referring to the drawing, the numeral 1 designates the sheet of fabric, which fabric is run through a composition, for instance

paraffin for rendering the same translucent for use in connection with poultry houses, or wherever a translucent housing is desired, for instance porches of homes or hospitals, where this type of material is coming into extensive use. It has been found that where the fabric 1 is used with a coating, the sheets of material, especially where large will often bulge, and the sheets can not be stretched to position without damage to the sheet. It has also been found that where a very heavy fabric is used, the translucency thereof is materially reduced, consequently ultra violet rays are cut off. To obviate the above difficulties the fabric 1, preferably during the course of manufacture is provided with transversely and longitudinally disposed threads 2 and 3, woven therein or stitched therein as desired, and which threads are heavier than the thread forming the fabric 1. Threads 2 and 3 preferably cross each other at right angles, thereby forming square areas *a*, which receive a thicker layer of material as clearly shown in Figure 3, as it has been found that this area will absorb more of the processing mixture when divided into areas and during the cooling process tends to give a more evenly finished product on account of the relative thickness thereof, consequently insures longer and more satisfactory wearing qualities. The large strands 2 and 3 may be formed from fibre or from wire, and applicants do not limit themselves to the particular material, or to the crossing of the strands 2 and 3 at right angles, as it is obvious the strands may cross at other angles. It will be noted by providing the reenforcing strands 2 and 3, thicker zones of coating material are insured and a sheet of material may be stretched to its position without damaging the same, and stretching of the material is obviated. It will also be seen by providing the large reenforcing strands 2 and 3 a relatively light weight fabric 1 may be used which will give the maximum transparency, but at the same time the reenforcing strands 2 and 3 furnish the additional strength for forming a strong material and all of the advantages of the undesirable heavy fabric without the objectionable features thereof, that is lack of transparency and slow absorption, as well as labor incident to handling heavy fabric during the course of manufacture.

From the above it will be seen that a reinforced glass substitute is provided having a fabric base which is reenforced by larger strands crossing each other angularly, and 5 a better and thicker coating may be applied to the fabric incident to the rectangular shaped areas formed by the cross strands.

The invention having been set forth what is claimed as new and useful is:—

- 10 1. A glass substitute for transmitting ultra violet rays comprising a woven fabric base having reenforcing textile strands extending through said fabric base in spaced relation and of heavier material than the other 15 strands of the fabric base and a translucent

material carried by said fabric base and re-enforcing textile strands.

2. A glass substitute for transmitting ultra violet rays comprising a woven fabric base having reenforcing textile strands extending through said fabric base, said reenforcing textile strands being in spaced crossed relation thereby forming zones between the re-enforcing textile strands and a translucent material carried by said fabric base and re- 25

enforcing textile strands.

In testimony whereof we hereunto affix our signatures.

LEROY E. SPENCE.
JOSEPH R. HOGATE.
